United States Patent Office

Des. 230,661
Patented Mar. 5, 1974

230,661

HANDBAG

Jacqueline H. Andrews, Patrick St.,
Ashland, Va. 23005

Filed Feb. 15, 1972, Ser. No. 226,654

Term of patent 14 years

Int. Cl. D3—01

U.S. Cl. D87—3 C

FIG. 1

FIG. 4

FIG. 1 is a side perspective view of a handbag showing my new design;

FIG. 2 is an end elevational view of the end opposite that shown in FIG. 1;

FIG. 3 is a side elevational view of the side opposite that shown in FIG. 1; and

FIG. 4 is a top plan view.

I claim:

The ornamental design for a handbag, as shown.
